UNITED STATES PATENT OFFICE.

JOHN W. EISENHUTH, OF BROOKLYN, NEW YORK.

REVERSING MECHANISM FOR MOTORS.

1,029,430.

Specification of Letters Patent. Patented June 11, 1912.

Application filed November 21, 1908, Serial No. 463,803. Renewed September 29, 1911. Serial No. 651,986.

To all whom it may concern:

Be it known that I, JOHN W. EISENHUTH, a citizen of the United States, residing at Brooklyn, in the county of Kings and State 5 of New York, have invented certain new and useful Improvements in Reversing Mechanisms for Motors, of which the following is a specification, reference being had therein to the accompanying drawing.

10 This invention relates to motors, and has specially in view an improved reversing mechanism therefor in which the reverse of the motor is obtained by manipulating the valves thereof.

15 Another object is the provision of an operating shaft for the valve shafts which will turn only in one direction regardless of the direction in which the motor is turning.

A further object is to provide a construction 20 which will operate positively on the valve shafts and instantaneously set the valves for the direction in which it is desired to have the motor operate.

The device is primarily intended for use 25 with hydro-carbon motors of the multiple cylinder type, but it is to be understood, however, that the invention is not to be limited to such application, since, from what will appear later, it can be readily understood 30 how the invention may be applied to other types of engines and motors now in use. For purposes of illustration I have selected a hydro-carbon motor of the compound type, having the cylinders and valve 35 chests oppositely disposed, the crank shaft thereof being at all times in mesh with a vertically disposed shaft which, in turn is at all times in mesh with a reversing shaft.

Referring to the accompanying drawings— 40 Figure 1 is an end elevation of a hydrocarbon motor of the compound type, fitted with the present invention. Fig. 2 is a detail sectional view of the reversing mechanism thereof. Fig. 3 is a side elevation of a portion 45 of the operating rod. Fig. 4 is a transverse sectional view taken on the line 4—4, Fig. 2. Fig. 5 is a detail side elevation of one of the driven gears. Fig. 6 is a detail sectional view taken on the line 6—6, Fig. 1.

50 Referring to said drawings by numerals, 1 designates the crank case of a hydrocarbon motor from which the crank shaft 2 projects and carries a gear 3 on its outer end

which is at all times in mesh with a pinion 4 mounted on a hub 5 carried by the lower portion of a vertically disposed shaft 6 the upper end of which carries a hub 7 having a beveled pinion 8 mounted thereon, and which is in mesh with two oppositely disposed vertically arranged beveled gears 9 and 10, mounted on a horizontally disposed hollow shaft 11 extending across the base of the motor. The beveled gears 9 and 10 are retained in spaced relation on the hollow shaft 11 by means of a bushing 12. Referring more particularly to Fig. 2 of the accompanying drawings, it will be observed that, the said beveled gears 9 and 10 are each provided with a shouldered hub 13 which loosely fit the hollow shaft 11, and adjacent to each gear, the said hub is provided with a clearance chamber 14. Each hub is provided with a diagonally disposed slot 15 one end of which communicates with the clearance chamber 14, the other end terminating in a longitudinally extending slot 16. The hollow shaft 11 is provided with a longitudinally extending slot 17 adjacent to and co-operating with the slotted portion of the hub, as will presently appear.

A valve shaft operating rod 19 is slidable through the hollow shaft 11 and is retained in spaced relation thereto by means of space blocks 20. Said rod is also provided with locking pins or lugs 21 which may be carried by one of the spacer blocks, said pins or lugs being arranged on said rod so that they will project through the slots 17 to the shaft 11 and alternately engage with one or the other of the slots of the hub of the beveled gears 9 and 10 to lock the same to the shaft 11. The ends of hollow shaft 11 project into gear casings 22 which are supported at opposite sides of the engine or motor by means of bracket bearings 23 which support the shaft 11 and have mounted thereon a worm or other pinion 24 which is held in mesh with a pinion 25 carried by the lower end of each of the shafts 26 and 26^a. One end of the rod 19 projects through and beyond one of the gear casings 22, and is provided with an extension 27 terminating in a ball 28 which is seated in a socket 29 carried by the lower end of a hand-operated lever 30 which has a bracket connection 31 with the motor.

The operation of the invention is as fol-

lows: Assuming the parts of the reversing mechanism to be in the position shown in Fig. 2, it will be seen that one of the locking pins 21 of the rod 19 is projecting through 5 the slot 17 of the shaft 11 and into the clearance chamber 14 of the hub of the beveled pinion 10. The other locking pin is projecting through the slot 17 of the shaft 11 and the slot 16 of the hub of pinion 10 9, and, therefore, said pinion 9 is locked to the shaft 11 and imparts its movement thereto, while pinion 10 is turning idly in the opposite direction on said shaft. To reverse this operation the lever 30 is rocked to im- 15 part a sliding movement to rod 19 through the shaft 11, causing the locking pin which has been holding pinion 9 to the shaft 11 to move into the clearance chamber of said pinion and simultaneously remove the other 20 locking pin from the clearance chamber of pinion 10 and through the diagonally disposed slot 15 and with the slot 16 of the hub of pinion 10 and the slot 23 of shaft 11, and thereby lock shaft 11 to pinion 10. This 25 movement immediately alters the operation of the engine or motor and causes the crank shaft 3 thereof to rotate in an opposite movement, which movement is communicated to shaft 11 through the gears 4, 8 and 10 and shaft 6. It will thus be seen that irrespec- 30 tive of the direction in which the motor is operated the hollow shaft 11 will be rotated in but one direction.

What I claim as my invention is:

35 1. In a motor, the combination with a crank shaft and valve shafts, a hollow shaft, gear wheels loosely mounted thereon, the hubs of which are each provided with a slot, a rotating rod within said hollow shaft, a
40 connection between said rod and valve shafts, means on said rod to enter the slots of the hubs to render either of the gears active on the hollow shaft, the construction being such that when the rod has rendered either of
45 the gears active the motor will have reversed its operation without changing the direction of the rotation of the hollow shaft.

direction of the rotation of the hollow shaft.

2. In a motor, the combination with a crank shaft and valve shafts, of a hollow shaft provided with slots, gear wheels loosely mounted thereon and provided with slotted hubs, a rotating rod slidably mounted in said hollow shaft, a gear connection between the ends of said rod and said valve shafts, and lugs carried by said rod for engagement with the slotted hubs of said gears and the slots of the hollow shaft to render either of said gears active to effect a reverse of operation of the valve shafts without changing the direction of rotation of the hollow shaft.

3. In a motor, the combination with a crank shaft and valve shafts, of a hollow

shaft having loosely mounted gears operated by said crank shaft, said gears being provided with slotted hubs, a rod slideable through said hollow shaft and adapted to selectively engage with said hubs to lock the same to the hollow shaft, and a gear connection between said valve shafts and the ends of said hollow shaft. 65 70

4. In a motor, the combination with a crank shaft and valve shafts, of a hollow shaft, oppositely disposed gears on said hollow shaft, hubs for said gears provided with slots, a rod slideable in said hollow shaft, lugs carried by said rod for selective engagement with the slotted hubs of said gears to lock the same to the hollow shaft, a connection between the crank shaft and said 80 gears; and a connection between the ends of said hollow shaft and said valve shafts.

5. In a motor, the combination with a crank shaft and valve shafts, of a hollow shaft, hubs spaced apart on said shaft and each provided with an end clearance chamber, said hubs being slotted, a gear for each hub, a rod slidably mounted in said hollow shaft, lugs carried by said rod, said lugs being adapted to engage with the slots of said hubs to lock the same to said hollow shaft and being arranged so that when one is engaged with a hub the other will be projecting into said clearance chamber, a connection between said crank shaft and said gears, and a connection between said hollow shaft and said valve shafts. 85 90 95

6. In a motor, the combination with a crank shaft and valve shafts, a hollow shaft provided with slots, hubs mounted on said hollow shaft and provided with slots adapted to communicate with the slots of said shaft, said hubs being provided with a clearance chamber, a gear carried by each hub, a rod 100 slidable in said hollow shaft, lugs carried by said rod and adapted to be passed through the slots of said hollow shaft and hubs, said lugs being arranged so that when one is locking a hub to the hollow shaft the other lug will be projecting into one of the clearance chambers; a shaft connection between said hub gears, and a connection between the hollow shaft 105 and said valve shafts. 110

7. In a motor, the combination with a 115
crank shaft and valve shafts, of a vertically
arranged shaft operated by said crank shaft,
a hollow shaft, gears on said hollow shaft
each provided with a slotted hub, said gears
being operated by said vertical shaft, a rod 120
slidable through said hollow shaft and
adapted to selectively lock said slotted hub
to said hollow shaft, and a gear connection
between said hollow shaft and said valve
shafts. 125

8. In a motor, the combination with a

crank shaft and valve shafts, of a vertically arranged shaft operated by said crank shaft, a hollow shaft, a pair of gears loosely mounted on said hollow shaft and held in spaced

5 relation, a hub for each gear, said gears being operated by said vertical shaft, a rod slidable through said hollow shaft, means carried by said rod for selectively locking said hubs to said hollow shaft, and a gear

connection between the hollow shaft and 10 said valve shafts.

In testimony whereof I hereunto affix my signature in presence of two witnesses.

JOHN W. EISENHUTH.
